2 SHEETS—SHEET 2.

A technical line drawing of a mechanical assembly, likely a valve or actuator. The drawing shows a central vertical axis with various components attached. Key parts include:

- 41: A rectangular component at the top.
- 42: A cylindrical component below 41.
- 54: A vertical rod or shaft.
- 55: A horizontal rod or lever.
- 56: A small rectangular component.
- 57: A vertical rod or lever.
- 37: A horizontal rod or lever.
- 38: A vertical rod or lever.
- 40: A horizontal rod or lever.
- 39: A vertical rod or lever.
- 21: A small rectangular component.
- 20: A vertical rod or lever.
- 19: A vertical rod or lever.
- 23: A vertical rod or lever.
- 25: A vertical rod or lever.
- 36: A horizontal rod or lever.
- 34: A horizontal rod or lever.
- 35: A horizontal rod or lever.
- 33: A rectangular component.
- 31: A vertical rod or lever.
- 32: A vertical rod or lever.
- 29: A vertical rod or lever.
- 26: A vertical rod or lever.
- 24: A vertical rod or lever.
- 22: A vertical rod or lever.
- 27: A vertical rod or lever.
- 28: A vertical rod or lever.
- 29: A vertical rod or lever.
- 30: A vertical rod or lever.

The assembly appears to be a complex linkage system, possibly for a valve or a similar control mechanism.

UNITED STATES PATENT OFFICE.

LE ROY C. CRIM, OF ALTMAR, NEW YORK

AUTOMATIC TRAIN-CONTROL SYSTEM.

1,132,450.

Specification of Letters Patent. Patented Mar. 16, 1915.

Application filed April 20, 1914. Serial No. 334,814.

To all whom it may concern:

Be it known that I, LE ROY C. CRIM, a citizen of the United States, residing at Altmar, in the county of Oswego and State of New York, have invented certain new and useful Improvements in Automatic Train-Control Systems, of which the following is a specification, reference being had to the accompanying drawings.

This invention relates to an automatic railway control system designed for operation in connection with the ordinary block signal system commonly employed upon railways for preventing the movement of the train into a block which is already occupied by another train.

One of the more important and particular objects of the present invention is to provide in a system for the automatic control of railways, electrically operated means for applying air to the brakes even though the engineer's control valve remains in release position, and simultaneously cutting off the motive power.

The invention has for a further general object to devise an electrically operated railway control system which may be installed in railways employing the block signal system, without necessitating any alterations in the latter, or greatly increasing the initial cost and subsequent maintenance of the railway equipment.

With the above and other objects in view as will become apparent as the description proceeds; the invention consists in certain constructions, combinations and arrangements of the parts that I shall hereinafter fully describe and claim.

For a full understanding of the invention, reference is to be had to the following description and accompanying drawings, in which—

Figure 1 is a diagrammatic view illustrating my invention as applied to the ordinary straight air brake system where the brakes are applied by the direct application of air to the brake cylinder piston. Fig. 2 is an enlarged section through the electrically operated air supply controlling valves.

Considering first that application of the present invention which is illustrated in Fig. 1 of the drawings, 5 designates the air pressure supplying tank which is replenished by a compressor 6 electrically driven from the source of current supply through the controller 7, a suitable pressure governor

8 being arranged in the circuit. A pipe 9 connects the pressure tank 5 with the train line pipe 10 to which one end of the brake cylinder 11 is connected. A motorman's control valve 12 is arranged in the branch pipe 9' which is connected to the pressure supply pipe 9. The piston 13 in the brake cylinder 11 is connected to the brake beams in the usual manner. The air supply pipe 9 is provided with a suitable gage 14, alarm whistle 15 and safety valve 16. All of the parts above referred to constitute the usual equipment for the common direct application air brake system. In the circuit wire 17 of the air compressor and pressure governor, a fuse block is located.

To the supply pipe 9 upon one side of the motorman's control valve 12, a branch pipe 18 is connected. The other end of this pipe 18 is connected to the valve casing 19. This casing is provided with an interior partition wall 20 as shown in Fig. 2 which divides the same into upper and lower chambers 21 and 22 respectively. This partition wall is formed with an opening 23 normally closed by the valve member 24. This valve member is fixed upon a rod 25 which is movable through suitable stuffing boxes arranged in the top and bottom walls of the casing 19. A vertical partition wall 26 is also arranged in the upper chamber 21 and provided with an opening 27 normally closed by the valve 28. To this upper chamber of the valve casing, one end of the pipe 29 is connected, the other end of said pipe being connected to the train line pipe 10. In the branch pipe 9', between the engineer's valve 12 and the pipe 29 a second valve casing 30 is arranged, said casing being also provided with a horizontal partition wall 31 which divides the same into upper and lower chambers to which the supply pipe 9 and the train line pipe 10 respectively are connected. This partition wall 31 has a central opening 32 therein to receive a valve member 33 on the lower end of a rod 34. This valve rod is connected to the valve rod 25 by means of a sleeve or nut indicated at 35, the bore of which is oppositely threaded at its ends, and it will be understood that by simply adjusting this nut, the valves 24 and 33 may be adjusted with respect to each other. The sleeve 35 is securely held in its adjusted position by suitable set screws 36. The valve member 28 is provided with a rod 37 which extends through the wall of the casing 19

and through a sleeve 38 fixed to the exterior of the casing wall. A coil spring 39 is arranged within this sleeve upon the valve rod and a nut 40 is threaded upon the end of said rod, whereby the tension of the valve spring may be adjusted.

41 indicates a solenoid, the core 42 of which is opposed to the upper end of the valve rod 25. A coil spring 43 is connected to the upper end of said core to normally hold the same in an elevated position and out of engagement with the valve rod. One end of the solenoid winding 44 is connected to a contact shoe 45 carried by the train car. The other end of the winding 44 is connected to one of the track rails indicated at R.

46 indicates a semaphore pole or post upon the upper end of which the semaphore arm 47 is pivotally mounted in the usual manner. To a circuit closing contact member 48 on one end of this arm, a wire 49 is connected, said wire extending from the conductor rail 50 which is arranged at one side of the track and insulated from the ground. A contact arm 51 is mounted upon the upper end of the post with which the contact 48 on the semaphore arm is adapted to engage when the semaphore is in its danger indicating position, and to this latter contact element 51, a current conducting wire 52 is connected, said wire being connected at its other end to the trolley wire 53 or other source of electric current supply.

35 As thus far described, it will be manifest that when a train occupies a block, and the semaphore is disposed in danger position, the contacts 48 and 51 being engaged, upon the approach of another train, to said block, 40 the shoe 45 carried thereby will strike the conductor rail 50, and thereby close the circuit from the trolley wire 53, through wire 52, the contacts 48 and 51, wire 49, the rail 50, shoe 45 and the solenoid winding 44 through the track rails to the ground, it being of course understood that the solenoid winding is connected to the rails through the car wheels. The solenoid is thus energized so that the core 42 thereof moves 50 downwardly and engages the upper end of the valve rod 25. The valve 24 is thus forced downwardly to its open position against the action of the spring 24' which normally tends to hold said valve upon its seat, while the lower valve 33 is moved to its closed position. Air will thus enter from the supply pipe 9 through the branch pipe 18 into the lower chamber 22 of the valve casing 19, and pass into the upper chamber 60 of said valve casing. The pressure of the air against the valve 28 forces said valve to its open position so that the air may enter the pipe 29 and the train line pipe 10, through which the air is supplied and to the 65 brake cylinder 11. The brake cylinder pis-

ten is thus operated and the brakes applied. It is apparent that this operation will take place, though the motorman may neglect to return the control valve to its lap position and leave the port with which said supply pipe 9 is connected open to the atmosphere.

The application of the brakes is thus assured. In order to hold the valve 24 in its open position, after the circuit closing shoe 45 moves out of engagement with the conductor rail 50, I provide a hook 54 on the solenoid core 42 with which a spring held latch member 55 is adapted to engage, said member being secured upon one end of a rod 56 mounted for sliding movement in a suitable supporting bracket 57. When it is desired to shut off the supply of air from the pressure cylinder to the train line pipe, the motorman pushes upon the rod 56 to release the solenoid core so that the same is moved upwardly by the spring 43, thus permitting the valve spring 24' and the air pressure in the lower chamber of the valve casing 19 to return the valves 24 and 33 to their normal positions.

90 In addition to the automatic application of the air brakes, the motive supply current is also automatically cut off from the controller and consequently from the car motors. To this end, I provide a second solenoid 58 having a winding 59, one terminal of which is connected to the track rails through the car wheels, and the other terminal connected to the shoe 45. This solenoid is also provided with a second overload 95 winding 60, one terminal of which is connected to the wire 17 leading from the controller to the air compressor. The other terminal of this winding 60 is connected to the movable contact of a circuit breaker indicated at 61. The other movable contact of the circuit breaker is electrically connected to the trolley pole 62, such connection including a resistance 63. This movable contact is adapted to be actuated by the core of 100 the solenoid 58. It will be noted that the emergency winding 59 and the overload winding 60 are arranged upon the same solenoid. The winding 59 is of course heavy enough so that it will operate the circuit 105 breaker 60 at the maximum load adjustment of said solenoid. If for any reason however, this double winding of the solenoid is not desirable, it will be understood that separate solenoids may be used. It will 110 be apparent from this latter description that when the circuit is closed through the shoe 45 and the track rails in the manner above stated to automatically apply the air brakes, the coil 59 is also energized to operate the 115 circuit breaker and thus deenergize the overload coil 60, to cut off the supply of current to the motors, through the controller 7. In this manner, the train may be 120 instantly brought to a stand still and pre- 130

vented from entering the block which is already occupied by another train. It is to be noted that the exciting current for the application of the brakes and cutting off 5 the motive power, is taken direct from the trolley wire through the engaged contacts of the semaphore, and not from the motor circuit, thereby avoiding all liability of a failure of operation due to the trolley wheel 10 jumping off of the wire at the critical moment.

From the foregoing description taken in connection with the accompanying drawings, it is believed that the manner of installation, operation and several advantages 15 of my improved electric railway control system in its several applications will be clearly and fully understood. The invention being simple in its construction, will not require 20 an expensive additional equipment for the cars, or in any way necessitate alterations in the present construction of the block signal system, now in general use. It will also be obvious from the foregoing that my improved 25 control system will positively operate to stop the forward movement of the train into a block which is already occupied, thus absolutely avoiding all possibility of collision. It will be obvious that the several 30 valves and their operating parts may be arranged in the cab of the train car or locomotive in any desired position, most convenient for the motorman or engineer. The invention is also capable of a great many 35 modifications in the form, proportion and arrangement of its detail parts and I therefore reserve the privilege of resorting to all such legitimate changes as may be fairly embodied within the spirit and scope of the 40 invention, as claimed.

Having thus described the invention, what is claimed is:

1. In a system of railway control, the combination with an air brake system including 45 an air supply pipe and motorman's valve, of a normally open valve, branch pipes connected to the supply pipe and to the brake cylinders, said open valve and the motorman's valve being located in one of said 50 branch pipes, a normally closed valve in the other of said branch pipes and controlling

air communication through the same, means for adjustably connecting said latter valve to the normally open valve, electrically controlled means for simultaneously operating 55 said valves when the motorman's valve is in exhaust position whereby the first named valve is closed and the second valve opened to establish communication through the second named pipes between the supply pipe 60 and the brake cylinders, a latch device for holding the valves in the latter positions, and manually operable means to actuate said latch device to release said valves to permit the same to return to their respective normal 65 positions.

2. In a railway control system, the combination with an air brake system including an air supply pipe and the motorman's valve, of a normally open valve, branch 70 pipes connected to the supply pipe and to the brake cylinders, said latter valve and the motorman's valve being located in one of said branch pipes, a valve casing having two compartments to which the other of the 75 branch pipes is connected, a valve normally closing communication between said compartments, means for adjustably connecting said valve to the normally open valve, a vertical wall arranged in one of said compartments between one of the branch pipe connections and said valve, a valve mounted in said wall, means for operating said valves to close the valve in the supply pipe and open said normally closed valve to establish 80 communication between the compartments of the valve casing, means for varying the air pressure necessary to move the valve in said vertical wall to its open position and establish communication through said 85 branch pipe, a latch device for holding the connected valves in their latter positions, and means for manually operating said device to release the valves and permit the same to return to their respective normal 90 positions.

In testimony whereof I hereunto affix my signature in the presence of two witnesses.
